(57) **CLAIM**

The ornamental design for a communication device, as shown and described.

DESCRIPTION

FIG. 1 is a front perspective view of a communication device according to the invention.

FIG. 2 is a front view of the communication device of FIG. 1.

FIG. 3 is a rear view of the communication device of FIG. 1.

FIG. 4 is a left side view of the communication device of FIG. 1.

FIG. 5 is a right side view of the communication device of FIG. 1.

FIG. 6 is a top plan view of the communication device of FIG. 1; and,

FIG. 7 is a bottom plan view of the communication device of FIG. 1.

1 Claim, 7 Drawing Sheets
